PATENTED AUG. 2, 1904.

C. H. HANSON.

METHOD OF FASTENING FENCE WIRES.

APPLICATION FILED OCT. 14, 1903.

NO MODEL.

UNITED STATES PATENT OFFICE.

CHARLES H. HANSON, OF WELAND, CANADA, ASSIGNOR TO THE FROST WIRE FENCE COMPANY, OF CLEVELAND, OHIO, A CORPORATION OF OHIO.

METHOD OF FASTENING FENCE-WIRES.

SPECIFICATION forming part of Letters Patent No. 766,345, dated August 2, 1904.

Application filed October 14, 1903. Serial No. 176,985. (No model.)

To all whom it may concern:

Be it known that I, CHARLES H. HANSON, a citizen of the United States, residing at Welland, in the Province of Ontario and Dominion of Canada, have invented a new and useful Improvement in Methods of Fastening Fence-Wires, of which the following is a specification.

This invention relates to a method of connecting the intersecting wires of wire-fences.

One of the fastenings for wire fences heretofore used consists of a clip having tapering slots in its wings, which is applied to the wires by placing one wire between the wings and 15 against the back of the clip, then inserting the other wire through the slots of the wings, and finally driving the clip lengthwise of its slots for clamping or wedging the wires against each other. This method of fastening together 20 the wires has been found objectionable because the fibers of the wires are liable to be cut by the clip sliding on the wires, thereby weakening the fence. Furthermore, this former fastening is liable to slip in being applied or 25 when subjected to strain while in use, thereby displacing the wires and producing an unsightly fence.

The principal object of this invention is to fasten the intersecting wires of a fence in such 30 manner that they are securely held against displacement.

The invention has the further object to provide a method of fastening the wires whereby the same will become interlocked by indenting each other and by which the fastening can 35 be effected without weakening the wires.

In the accompanying drawings, Figure 1 is a fragmentary perspective view of two intersecting fence-wires having the connecting-clip 40 applied thereto according to my improved method. Fig. 2 is a horizontal section of the same, taken above the clip and showing the condition of the connection preparatory to pinching the clip against the wires. Fig. 3 45 is a similar view showing the condition of the

parts after being fastened. Fig. 4 is a vertical section in line 4-4, Fig. 3. Fig. 5 is a horizontal section in line 5-5, Fig. 4.

Similar letters of reference indicate corresponding parts throughout the several views. 50

A represents one of the main or horizontal fence-wires, and B one of the stays or vertical fence-wires which usually intersect each other at right angles.

C represents the clip employed in my improved method of connecting the main and stay wires of the fence. This clip is U-shaped and provided in each of its wings c with a longitudinal slot D, forming a longitudinal bar E, which is substantially parallel with the back 60 or bight f, which connects the wings at one edge.

In fastening the intersecting fence-wires together the clip is first slipped over the main wire until its back engages the same. The 65 stay-wire is then inserted in the slots of both wings, so that the main wire is confined between the stay-wire and the back of the clip. Fig. 2 shows the clip and wires assembled in this manner. The longitudinal bars E and 70 the back of the clip are then pinched toward each other, as shown in Figs. 1 and 3, whereby the wires are securely clamped together. Sufficient pressure is preferably exerted in pinching the clip upon the wires to cause the 75 wires to slightly indent each other, as shown at g g' in Figs. 4 and 5, thereby firmly interlocking the wires. The wires are thus prevented from becoming displaced relatively to each other when subjected to strain in the longitudinal direction of either wire, thereby 80 avoiding the unsightly appearance frequently presented by fences in which the wires have been shifted out of their proper position by animals or from other causes. Inasmuch as 85 the pressure for pinching or clamping the clip on the wires is applied transversely of the wires the clip and the wire passing through its slots are not liable to slip or be shifted bodily. The liability of short-bending the 90

wires or cutting their fibers on the surface and the consequent weakening of the fence is therefore avoided.

In order to obtain the best clamping effect 5 of the bars E against the wire in the slotted wings, this wire is placed at one end of the slots. This permits the bars when bent or pinched to embrace this wire to a greater extent, thus increasing the hold thereon correspondingly.

For the purpose of retaining the stay-wire at one end of the slotted wings each of the bars E is provided centrally with an inwardly-projecting swell or enlargement h, which reduces the width of this part of the slot so that it is narrower in the middle than the stay-wire. By this means the stay-wire is prevented from sliding from one end of the slots to the other, thereby permitting of keeping 15 all the clips of the same stay in alinement if they have been properly placed on the wire and insuring a uniform and neat appearance of the finished fence. Both ends of the slots in the clip are preferably made large enough 20 to receive the stay-wire. The erection of the fence is thereby facilitated, because the clip can be applied at either end to the wire, and the necessity for exercising care in assembling 25 the parts is avoided.

30 After the bars E have been pinched against the stay-wire the central part of each bar has the form of a reentrant angle and is located inwardly out of line with its ends, which latter are both rigidly connected with and supported by the ends of the respective wing, as 35 represented in Fig. 3. When the bars are thus bent or pinched, they form toggle-like braces which enable them to offer a powerful 40 resistance to any strains tending to bend them outwardly or away from the stay-wire into an inoperative position, thereby effectually holding the clip in its locked or operative position.

My improved method of applying the clips 45 to the fence-wires can be practiced not only while assembling the parts on the field, but

also while weaving the fence complete in a loom.

I claim as my invention—

1. The herein-described method of uniting 50 the intersecting wires of a fence by means of a clip having longitudinal slots in its wings which are closed on all sides forming bars each connected at both ends to the wings, which method consists in first applying the 55 clip to the wires so that one wire is arranged in the slots of both wings and the other wire between the first-mentioned wire and the bight of the clip, and then pinching or bending said bars toward said bight, substantially as set 60 forth.

2. The herein-described method of connecting the intersecting main and stay wires of a fence by means of a clip having longitudinal slots in its wings which are closed on all sides 65 forming a bar on each wing which is connected to the wing at both ends, which method consists in first slipping the clip over the main wire and engaging its back with the same, then inserting the stay-wire in one end of both 70 slots, and then pinching the back and the bars of the clip for gripping the wires in the clip toward each other and pressing the same against each other, substantially as set forth.

3. The herein-described method of connecting 75 the intersecting main and stay wires of a fence by means of a clip having longitudinal slots in its wings which are closed on all sides forming a bar on each wing which is connected to the wing at both ends, which method consists in first slipping the clip over the main 80 wire and engaging its back with the same, then inserting the stay-wire in one end of both slots, and then pinching said bars midway of their ends in the form of a reentrant angle, 85 substantially as set forth.

Witness my hand this 7th day of October, 1903.

CHARLES H. HANSON.
